Primary Examiner—Donald P. Walsh*Assistant Examiner*—M. N. Pandozzi*Attorney, Agent, or Firm*—Benoni O. Reynolds[57] **CLAIM**

The ornamental design for a pocket insert for tools, as shown and described.

DESCRIPTION

FIG. 1 is a front elevational view of a pocket insert for tools showing my new design;

FIG. 2 is a rear elevational view thereof;

FIG. 3 is a left side elevational view thereof; the right side elevational view is a mirror image;

FIG. 4 is a top plan view thereof; and,

FIG. 5 is a bottom plan view thereof.

The broken line showing the outline of a pocket in FIG. 1 and FIG. 2 is for illustrative purposes only to show environmental structure and forms no part of the claimed design. The broken lines within the insert in FIG. 1, FIG. 2 and FIG. 5 shows the stitching observable on the insert.
